CLAIM

We claim the ornamental design for optical head mounted display with transparent visor, as shown and described.

DESCRIPTION

FIG. 1 is a perspective view of an optical head mounted display with transparent visor showing our new design; FIG. 2 is a front elevation view thereof; FIG. 3 is a rear elevation view thereof; FIG. 4 is a right elevation view thereof; FIG. 5 is a left elevation view thereof; FIG. 6 is a top plan view thereof; FIG. 7 is a bottom plan view thereof; and, FIG. 8 is another perspective view thereof.

Any broken lines and unshaded portions contained within broken lines are directed to environment or unclaimed features. The broken lines form no part of the claimed design.

1 Claim, 8 Drawing Sheets
